Term of patent 14 years

Int. Cl. D17—01

U.S. Cl. D56—9

FIG. 1 is a front perspective view of an electronic piano or similar article, showing one form of my new design;

FIG. 2 is an end perspective view of the form shown in FIG. 1;

FIG. 3 is a rear perspective view of the form shown in FIG. 1;

FIG. 4 is a front perspective view of an electronic piano or similar article, showing a second form of my new design;

FIG. 5 is an end perspective view of the form shown in FIG. 4;

FIG. 6 is a front perspective view of the form shown in FIG. 4, with an arm board pulled out to operating position; and

FIG. 7 is an end elevational view of the form shown in FIG. 4 with an arm board pulled out to operating position.

The dominant features of my design reside in the portions shown in full lines.

I claim:

The ornamental design for an electronic piano or similar article, as shown and described.
